The ornamental design for automobile tire tread, as shown and described.

DESCRIPTION

FIG. 1 is a front view of an automobile tire tread, showing the new design, a top plan view thereof and a bottom plan view thereof appearing the same as the front view;

FIG. 2 is a rear view of the automobile tire tread;

FIG. 3 is a right side view of the automobile tire tread;

FIG. 4 is a left side view of the automobile tire tread;

FIG. 5 is a fragmentary front view, showing in enlargement the portion of 5—5 in FIG. 1;

FIG. 6 is a cross-sectional view, taken along lines 6—6 and in the direction of arrows in FIG. 5;

FIG. 7 is a right perspective view of the automobile tire tread; and,

FIG. 8 is a left perspective view of the automobile tire tread. The even broken lines in the drawings represent environmental structure only and form no part of the claimed design. The dot-dash broken lines define the boundaries but form no part of the claimed design.
